UNITED STATES PATENT OFFICE.

GRANT H. LEITNER, OF TOLEDO, OHIO.

SIGNAL MEANS FOR AUTOMOBILES.

Application filed March 18, 1927. Serial No. 176,367.

This invention relates to signal devices, but particularly to switches for direction indicating signals for automobiles.

Objects of this invention are to provide a switch for attachment to a pedal of an automobile, which switch is simple in construction, reliable in operation, and has the new and improved features of construction and arrangement hereinafter described.

10 The invention is shown by way of illustration in the accompanying drawings, in which:

Fig. 1 is a top plan view of the pedal embodying the invention; Fig. 2 is an edge view of the pedal; and Fig. 3 is an enlarged view 15 of the pedal with the top plate removed and showing the wiring diagram for the signals.

The illustrated embodiment of the invention comprises a pedal having a metal back plate 1 secured to a mounting plate 2 by bolts 20 3 and nuts 4. The mounting plate 2 is integral with the pedal lever 5. Fixed to the upper surface of the back plate 1 is a plate member 6 of electrical insulating material, and this plate is held stationary by the bolts 3.

25 Suitably fixed to the insulating plate member 6 are contact pieces 7, 8 and 9. The contact pieces 7 and 8 are arranged in diametrically opposed relation at opposite sides of the plate member 6, and the contact piece 9 projects outwardly from the lower side of the plate 6, and is disposed in an arcuately shaped recess 10. Extending from the contact pieces 30 7, 8 and 9 are leads 11, 12 and 13, respectively, and these leads extend through an opening 14 in the back plate 1. As shown, channels are formed in the insulating plate 6 so that the leads are disposed beneath the surface of the plate.

As diagrammatically shown lead 11 extends 40 to a signal 15 marked R, the lead 13 extends to a signal 16 marked S, while the lead 12 extends to a signal 17 marked L. The letters R, S, L indicate Right, Stop and Left, respectively, and are for the purpose of indicating 45 stopping or intention of turning to the right or left.

A plate member 18 is formed with an opening 19 within which the insulating plate 6 is disposed. The sides of the plate 6 are spaced 50 from the sides of the opening 19. The plate member 18 may be of insulating material, and extending around the opening 19 is a conducting strip 20 connected thereto by tacks 21. The strip 20 is connected by a lead 22 with 55 one side of a battery 23.

The plate 18 is slidably and oscillatingly mounted on the back plate 1, and, as shown, is formed with a projection 24 provided with an elongate opening 25. Disposed within the opening 25 is a head 26 of a bolt 27 which extends through the back plate 1 and mounting plate 2, and is held in place by a nut 28. The elongate opening 25 is shouldered to receive the under side of the bolt head 26.

It will be apparent that the member 18 65 may be rocked about the bolt 27 relative to the insulating plate member 6, and also that it may slide relative to the plate member 6, and that when so slid the contact piece 9 will be brought into engagement with the conducting 70 strip 20 to close the battery circuit with the signal 16.

Rocking movement of the member 18 to the right brings the contact piece 7 into engagement with the conducting strip 20 for closing 75 the battery circuit with the signal 15, while rocking movement of the member 18 to the left brings the contact piece 8 into engagement with the conducting strip 20 and closes the battery circuit with the left signal 17. 80

For normally holding the contact pieces 7, 8 and 9, out of engagement with the contact strip 20, coiled springs 29 are disposed in sockets 30 in the insulating plate member 6, and the outer end of each spring bears 85 against an annular shouldered member 32 which extends into the spring. The diameter of the spring 29 is less than the socket 30 so that the member 18 may be freely rocked relative to the plate 6. Rotatably engaging 90 the bearing member 32 is a screw 31, which is screwed into the plate 18 with its outer end approximately flush with the edge of the plate. By means of a screw driver, the screw 31 may be adjusted to regulate the tension of 95 the spring 29. The contact strip 20 is insulated from the screw 31 and bearing member 32 by an insulating sleeve 33. It will be seen that the springs 29 are arranged on opposite sides of the projecting portion 24 so as 100 yieldingly to resist sliding and rocking movement in the manner described.

Fitting over the top of the plate member 18 is a cover plate 32, which has upstanding side flanges 33 and is secured to the plate member 18 by screws 34. A rubber pad 35 is preferably secured to the top of the plate 32 to prevent the foot from slipping when 105 operating the mechanism.

From the above description, it is manifest 110

that by pushing forward with the foot on the top of the pedal, which is the natural movement when operating the associated pedal, the contact piece 9 is brought into engagement with the conducting strip 20 for energizing the stop signal 16. Upon turning the foot to the right, the contact piece 7 is engaged by the conducting strip 20 to energize the right signal 15, and a rocking or turning movement in the opposite direction moves the conducting strip 20 into engagement with the contact piece 8 to energize the left signal 17.

These are natural movements in the operation of the automobile and enable the signaling means to be readily and efficiently handled without additional thought or manipulation on the driver's part.

While I have shown and described a construction which is the best form known to me at the present time, it is to be understood that numerous changes in details of construction and arrangement may be effected without departing from the spirit of the invention, especially as defined in the appended claims.

What I claim as new and desire to secure by Letters Patent is:

1. A switch having a pair of members, one member being within the other, contacts on the side edges of respective members, a pivot for one member to permit rocking movement thereof for engaging the contact on the side edge of one member with the adjacent contact on the other member.

2. A switch having a pair of relatively rotatable members, one member being within the other, a contact terminal in the outer edge of the inner member, and a contact terminal on the inner edge of the outer member whereby relative rocking movement of said members moves said terminals into engagement.

3. A switch comprising a pair of members arranged with one within the other and having relative sliding and rocking movements, two sets of contact terminals carried by said members respectively, one set being engage-

able upon relative rocking movement of said members and the other set upon relative sliding movement thereof.

4. A switch comprising a pair of members arranged with one within the other and having relative sliding and rocking movements, two sets of contact terminals carried by said members respectively, one set being engageable upon relative rocking movement of said members, the other set upon relative sliding movements thereof, and yielding means for normally holding the terminals of said sets out of engagement.

5. A pedal switch for automobiles comprising a plate adapted to be connected to the pedal lever, a member fixed to said plate having two contact terminals arranged in opposed relation, a member pivoted to said plate and disposed within said first member and having opposed contact terminals alternately engageable respectively with said first terminals when said second member is swung on its pivot, and means for yieldingly holding said second member in such position that said contact terminals are out of engagement.

6. A pedal switch for automobiles comprising a pair of members having relative pivotal and sliding movement, one member being adapted to be fixed to the pedal lever, said members being arranged one within the other, contact terminals on opposed sides of said members engageable respectively when relative pivotal movement is imparted to said members, and contact terminals on said members respectively engageable when relative sliding movement is imparted thereto.

7. A pedal switch for automobiles comprising a pair of members arranged one within the other and having relative crosswise sliding movement, contact terminals on said members respectively, and means for yieldingly holding said terminals separated from each other.

In testimony whereof I have hereunto signed by name to this specification.

GRANT H. LEITNER.
